UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY DRAFT-RIGGING.

1,288,660.

Specification of Letters Patent. Patented Dec. 24, 1918.

Application filed April 17, 1916. Serial No. 91,587.

To all whom it may concern:

Be it known that I, JOHN F. O'CONNOR, a citizen of the United States, residing at Chicago, in the county of Cook and State of Illinois, have invented a certain new and useful Improvement in Railway Draft-Rigging, of which the following is a full, clear, concise, and exact description, reference being had to the accompanying drawings, 10 forming a part of this specification.

This invention relates to improvements in railway draft rigging.

The object of the invention is to provide a draft rigging of high capacity wherein is employed a single arm yoke so arranged with other parts as to eliminate the necessity for stop castings.

The invention furthermore consists in the improvements in the parts and devices and 20 in the novel combination of the parts and devices herein shown, described or claimed.

In the drawing forming a part of this specification, Figure 1 is a longitudinal, central vertical section of a draft rigging showing my improvements in connection therewith. Fig. 2 is a horizontal sectional view taken substantially on the line 2—2 of Fig. 1. Figs. 3 and 4 are transverse, vertical sectional views taken on the lines 3—3 and 4—4 30 respectively of Fig. 1. Fig. 5 is a perspective view of the front follower block and Fig. 6 is a top plan view of the yoke.

In said drawing, 10—10 denotes the center sills or draft members provided with rear 35 slots 11, intermediate slots 12 and front slots 13, to accommodate a rear key 14, intermediate key 15, and coupler key 16, the latter being movable longitudinally within the slots 13, and the keys 14 and 15 stationary.

40 The draw bar 17 is connected by said key 16 with a one arm yoke designated generally by the reference A. Mounted on said key 15 is a front follower block 18 having an elongated slot 190 to accommodate said key 15 and permit said follower block to move inwardly under buff. The yoke A is provided with a lower horizontal portion 19 having an upwardly extending center rib 20, the sides 45 of said rib 20 being joined with the horizontal lower portion 19 by curved surfaces 21—21 to thereby form longitudinally extending seats for a pair of springs 22—22. At its rear end, the yoke A is provided with a

vertically arranged follower portion 23 having a rearward extension 24 slotted as indicated at 25 to accommodate the key 14 and permit the yoke to move forwardly under draft but preventing rearward movement of said yoke. The upper edge of said vertical rib 20 is preferably curved as indicated at 26 to form a seat for a third spring 27, said springs 22 and 27 being arranged parallelly with their axes coinciding with the corners of an equalateral triangle. At their front ends, said springs are seated on bosses 28 formed on the inner face of the follower block 18 and at their rear ends are seated on similar bosses 29 formed on the inner face of the rear follower portion 23 of the yoke. As clearly appears from Figs. 3 and 5, the underside of the front follower block 18 is recessed as indicated at 30 to fit over the rib 20 of the yoke and thereby permit the latter to move relatively to said follower. As shown in Figs. 1 and 2, said rib 20 is cut 75 away at its front portion as indicated at 31 thereby forming a shoulder 32 normally spaced from the follower 18 a distance corresponding to the permissible amount of compression on the springs. The block 18 is 80 tapered forwardly on its sides as appears from Figs. 2 and 5 and to correspond therewith, the side walls 33—33 of the yoke are similarly tapered whereby said follower block 18 is retained in central position. The 85 forwardly extended sides 34—34 of the yoke are slotted as indicated at 35 to accommodate the rearward movement of the coupler key 16 during the buffing action of the gear.

In operation, upon rearward movement of 90 the draw bar, the follower block 18 is forced rearwardly thereby compressing the springs against the rear follower 23 of the yoke. In draft, the follower block 18 is prevented from forward movement and the springs are 95 therefore compressed by the yoke and its rear follower 23 which moves forwardly over the rear key 14. In either buff or draft, the amount of movement is limited by the engagement of said shoulder 32 with the front 100 follower block.

From the preceding description, it will be seen that I have provided a spring draft gear of unusually high capacity since I am enabled to employ three springs arranged 105 parallelly and in a space which conforms to

the regulations of the Master Car Builders Association. All the parts may be cheaply manufactured and the gear readily assembled and disassembled. Furthermore, I 5 avoid the use of the usual stop castings.

Although I have herein shown and described what I now consider the preferred embodiment of my invention, the same is merely illustrative and I contemplate all 10 changes and modifications that come within the scope of the claims appended hereto.

I claim:

1. In a draft rigging for railway cars, the combination with a single arm yoke adapted 15 to be connected to a draw bar and having a rear follower movable in unison therewith, of a front follower, cushioning means between said followers, and coöperating means on said front follower and yoke to limit the 20 compression of the cushioning means.

2. In a draft rigging for railway cars, the combination with draft sills, of a single arm yoke, the latter having an integral rear follower provided with a transverse slot, a stationary key extending through said slot, the 25 rear follower being movable forwardly only relatively to said key, a front follower having a transverse slot, a stationary key extending through said slot in the front follower, the front follower being movable only rearwardly relatively to said key, and cushioning means between said followers, said one arm yoke remaining stationary under 30 buff.

3. In a draft rigging for railway cars, the combination with a yoke adapted to be connected to a draw bar, of a front follower associated with said yoke and movable with 35 respect thereto, a rear follower, cushioning means between said followers, and coöperating integral means on said front follower and yoke to limit the relative movement

therebetween and also to limit the compression of the cushioning means, said means being located in the center line of draft. 45

4. In a draft rigging for railway cars, the combination with a yoke adapted to be attached to a draw bar, of front and rear followers associated with said yoke, one of said followers being fixed with respect to the 50 yoke and the other movable relatively thereto, cushioning means interposed between said followers, and coöperating integral shoulders on said yoke and the follower movable with respect thereto, adapted to limit 55 the relative movement between said follower and the yoke.

5. In a draft rigging, the combination with draft sills, of a pair of fixed keys extending through said sills, a front follower 60 slidably mounted on the front key, a draw bar, a single arm yoke connected to said draw bar and extending rearwardly beneath said front follower, said yoke having an integral rear follower provided with a slot to 65 receive the rear key, and springs extending between said followers and located on the upper side of said yoke arm.

6. In a draft rigging, the combination with draft sills, of a pair of fixed keys extending through said sills, a front follower 70 slidably mounted on the front key, a draw bar, a single arm yoke connected to said draw bar and extending rearwardly beneath said front follower, said yoke having an integral rear follower provided with a slot to 75 receive the rear key, and springs extending between said followers, and coöperating means on the front follower and yoke to limit the compression of the springs. 80

In witness that I claim the foregoing I have hereunto subscribed my name this 12th day of April 1916.

JOHN F. O'CONNOR.
